ROTARY PUMP

Filed Oct. 25, 1933

UNITED STATES PATENT OFFICE

2,065,008

ROTARY PUMP

Alain Madlé, Bristol, Conn., assignor to Erban
Operating Corporation, New York, N. Y., a cor-
poration of New York

Application October 25, 1933, Serial No. 695,144

6 Claims. (Cl. 103—136)

My invention relates in general to pumps and in particular to rotary pumps as are used for distributing liquid lubricants and in one of its aspects it relates to a pump for supplying liquid lubricants to the interior of a rotating shaft.

In the design of rotating machinery, it may become necessary or desirable to build a pump for lubricating purposes into the system of rotating parts rather than to depend on an externally located pump, and the design of such constructions involves many considerations, the first of which is a lack of space, and the second of which relates to the problems encountered when the pump is driven from a shaft the direction of rotation of which may be either direct or reverse. The first requirement necessitates a pump which is compact in design and the second requirement necessitates a pump which will operate no matter what is the direction of rotation of its driving member.

The embodiment of my invention herein disclosed is particularly adapted for use with a reversible variable speed transmission employing systems of races and rolling bodies engaging the races by rolling frictional contact, such, for instance, as the one shown and described in my prior Patent No. 1,999,544 of April 20, 1935, as it may be mounted within the casing thereof, but it will be understood that it is not restricted to such use but is of more universal application, as heretofore indicated. For instance, by way of example, it would find ready and convenient application in the reversing gear casing of 1,788,108 Jacobsen of January 6, 1931.

One of the objects of my invention is therefore the provision of a pump of such compact design that it may be applied in a restricted space.

A further object of my invention is the provision of a pump adapted to be driven from a rotating shaft no matter what its direction of rotation, without any adjustment of the pump being required whenever the direction of rotation is reversed.

Another object of my invention is the provision of a pump of high efficiency and reliability and of such simplicity of construction that the parts are not exposed to excessive wear and the necessity for frequent replacement, and if such replacement should be necessary, it may be effected in a minimum of time and at a minimum of cost.

My improved pump construction by which the above object and other objects may be attained, involves an arrangement of parts symmetrical in relation to the direction of rotation of the pump, and comprises, in general, a rotating mem-

ber carrying valves of simple construction and a casing surrounding the same and adapted by their joint functioning, to generate the pressure necessary to cause circulation of the lubricating medium, and this effect will be accomplished no matter what the direction of rotation of the rotating member and without adjustment, manual or automatic, and it further comprises an oil circulation system adapted to supply oil to the rotating member and casing, no matter what the direction of rotation of said member.

While I have shown and illustrated all the features of my invention as combined into a unitary whole, of which all the parts cooperate, it is to be understood that as to certain phases of the individual parts thereof, such parts may be used in other combinations and relations and for other purposes, and not necessarily in the combinations and relations and for the purposes shown.

In order to show the application of my invention to a practical construction for the attainment of the above enumerated objects and such other objects as will hereinafter appear or be pointed out, I have illustrated one embodiment of my invention in the drawing, in which:

Figure 1 is a section view of my improved pump substantially on the line 1—1 of Figure 2, looking in the direction of the arrows;

Figure 2 is a sectional view of my pump substantially on the line 2—2 of Figure 1 looking in the direction of the arrows;

Figure 3 is a sectional view on the line 3—3 of Figure 1, looking in the direction of the arrows; and

Figure 4 is a diagrammatic view illustrating, in general form, one application of my pump.

Referring to the drawing in detail it will be observed that I have therein denoted by the letter A the assembly of parts constituting the rotating elements of my pump, by the letter B the assembly of parts constituting the enclosure surrounding the pump, and by the letter C the assembly of parts constituting the oil circulation system.

Considering first the rotating system A it will be seen that it is shown as comprising a hollow coupling member 10 designed for the connection to the transmission system, and to be located intermediate the same and the load, surrounding the coupling member, and secured thereto in any preferred manner, as by screw 11 and a sleeve 12 which carries the pressure generating elements. Located within the hollow of coupling member 10 is a distributing element 14, which is provided with suitable chan-

nels for the distribution of the lubricating fluid to the proper points. This element is caused to rotate with the coupling member in any suitable manner such as by key 13 and the outlet 5 portion thereby for practical reasons may conveniently be made in the form of a separate discharge nozzle 16.

The sleeve 12 carries an annular rib 17 provided on its periphery with pockets 18 in spaced 10 relation thereon. The annular rib 17 is flanked on both sides by annular rings 21 supported in fixed relation thereto, so as to form between them an annular groove. Located within the pockets 18 and having their ends in sliding but 15 liquid-tight contact with the walls of rings 21, are the rollers 18, which serve to generate pressure, as will be hereinafter described.

Running inwardly from the pocket 18 are channels 22, which communicate with holes 23 in 20 valve seats 24 seated within bores 26 in the coupling member 10.

The channels thus formed serve to establish communication between the pockets 18 and an annular channel 30 formed on the periphery 25 of distributing member 14. Passages 32 establish communication between channel 30 and the inner or distributing chamber 34 of the distributing member 14, from which the lubricating fluid is distributed to the various points at which 30 it is needed. Valve members 28, shown as in the form of balls adapted to seat on valve seats 24, are normally kept in place on their seats during the rotation of the rotating member A, by centrifugal force and thereby serve during rotation 35 to close the passage in the valve seat 23.

The casing B, which would ordinarily be relatively stationary, is conveniently made in two interfitting sections 60 and 62, having between them a space for the reception of the annular 40 rib 17 and its flanking rings 21, and they hold between them in fixed relation the ring 64, the inner surface of which is circular, but eccentric in relation to the rotating member A, and contacts with the same at one side, so that a crescent shaped space 36 is formed between the 45 rib 17 and the ring 64. It will also be observed that the rings 21 engage the sides of eccentric ring 64 in liquid-tight contact, whereby the space 36 is completely enclosed, except as hereinafter 50 mentioned: The bearing ring 65 likewise provides a liquid tight seal between its inner surface and the rollers 20 when the latter contact therewith. When the member A is rotating the rollers 20 will be urged outwardly against the 55 eccentric ring 64 by centrifugal force, and because of the liquid tight seal between that roller and the eccentric ring 64 and bearing rings 21, said rollers will act as pistons tending to push any oil located in the passage 36 in front of 60 them.

As clearly shown in Figures 1 and 3, the inner wall of the eccentric ring 64 is provided at the lower portion thereof with channels 38 and 40 which are of less width than the width of the 65 inner surface of the ring, so that the rollers 20 may not enter thereto, but are constrained to move along the inner eccentric cylindrical chambers of said ring. These channels are disposed on opposite sides of the ring 64 and communicate respectively with conduits 42 and 44 having at their lower ends inwardly opening one-way valves 46 and 48 respectively. The construction of these valves is illustrated in Figure 1, and it will be observed that the valves 70 proper 50 and 52, are resiliently held against

their respective seats 54 and 56 by springs 55 and 57. The inlet portions of the valves are necessarily below the level of the oil in the oil tank 58 and are so shown.

The operation of my pump will now be described. Referring particularly to Figure 1, and assuming that the member A is rotating in a counter-clockwise direction, and considering the roller 20 that is shown lowermost in Figure 1, it will be observed that as the member A rotates, the roller 20 will be urged outwardly against the inner cylindrical surface of the ring 64, and therefore will slide or roll over the portion of the ring containing the channel 40 without, however, being able to enter into or to obstruct the channel. In the meantime, the lowermost valve 28 has been pushed by centrifugal force against its valve seat 24, and there is therefore no communication between the lowermost pocket 18 and the oil distributing chamber 34. As, during the 20 counterclockwise rotation of member A, the roller proceeds in its course along the inner wall of ring 64 it enters the beginning of the crescent shaped chamber 36 until it reaches the end portion of the channel 40 which is shown as located 25 near the beginning of the upper right hand portion of Figure 1. As soon as this point is reached, owing to the liquid-tight contact between the roller, the rings 21 and ring 64, a piston effect is produced resulting in a suction in the channel 30 which serves to lift oil from the tank 58 into the channel 40 and into the beginning of the crescent shaped chamber 36. The succeeding roller 20 will now act on that portion of the oil 30 which is located in the beginning of the crescent shaped chamber 36, and as it passes the end of the channel 40, it will force this oil into the enlarged upper or middle portion of the chamber 36 and urge it counterclockwise by its piston action. As succeeding rollers act on the oil in 35 a similar manner, there will result a pressure in the enlarged upper or mid-portion of the chamber 36, located beyond the end of passage 40.

From the chamber 36 the oil may pass into the channel 38 and the left-hand portion of 45 chamber 36, until these spaces and the conduit 42 are filled with oil, but since valve 46 cannot open outwardly, there is no escape for the oil in this direction. On the other hand, escape of the oil through pockets 18 and valves 24, 28 50 is possible, only when the oil pressure against this valve exceeds the centrifugal effect tending to press the balls 28 against the seats 24.

When this point is reached, the pressure will 55 force the valves inwardly and force oil through the system of passages and channels into the distributing chamber 34, and from there to the parts to be lubricated. This last will be the normal operation of the pump.

In the foregoing description, it has been assumed that the pump is self-starting, requiring no priming, and it will be understood that under proper conditions enough suction will be built up in the passage 40, even when it is filled with air, to induce oil to enter conduit 44. Should 60 this not be possible, various devices may be resorted to, such as, by way of example, decreasing the length of conduit 44, immersing the pump in the oil tank, mounting the oil tank above the pump so as to secure gravity feed into the 65 pump or maintaining pressure in the oil tank.

When the direction of rotation of member A is reversed, the action is exactly the same, the valve 48 in this case closing while the valve 46 70 opens. The pressure is then built up on the right 75

hand side of Figure 1 instead of on the left hand side.

A convenient adjunct to the pump, although not necessary for its proper operation is an oil gauge and for this purpose the annular channel 68 may be provided in the casing 62 which has communication with the distributing chamber 34 through the passage 62 provided in the rotating member A. From the channel 68 the oil 10 is allowed to pass into the conduit 70 leading to an oil gauge located at any convenient point, such as the dash board of an automobile.

Figure 4 is intended to illustrate the suggested application of my invention. A motor is shown 15 coupled to a reversible transmission and intermediate the latter and the load is interposed a pump according to my invention. If a reversible motor is used, the pump might of course with advantage be installed between the motor and 20 the transmission, which might then be of irreversible type.

Nothing contained herein is to be interpreted 25 as limiting the use of my pump to use in connection with reversible rotating mechanisms as it will be obvious to those skilled in the art that because of its simple construction, it may possess high utility in connection with mechanisms rotating only in one direction.

While my invention has been described and 30 illustrated in relation to one embodiment thereof, it will be understood that the details thereof may be varied, and that the invention may be embodied in many other forms, as will be obvious to those skilled in the art, without departing 35 from the spirit thereof as defined in the appended claims. The disclosure herein is therefore to be considered to be by way of illustration merely, and not as limitative in any way.

Having thus described my invention and illustrated its use, what I claim as new and desire to 40 secure by Letters Patent is:

1. A rotary pump comprising an inner member free to rotate in opposite directions and a casing surrounding said inner member and 45 spaced therefrom except at one area of contact as the inner member is rotated, to provide a pressure chamber between it and the inner member closed by such area of contact, and said pressure chamber being generally crescent shaped, a distributing chamber within said rotating member, a channel connecting said chambers, and an element carried by and moving with said inner member within the channel and adapted to protrude into the pressure chamber, and automatically operative to propel the fluid in the pressure 45 chamber in that direction in which the inner member is rotated regardless of the direction of rotation, said element being mounted for limited movement within said channel and thereby serving automatically to close the channel except in 50 a direction from in front of said element as determined by the direction of rotation of said inner member, whereby said elements serve automatically to propel the fluid in the direction of rotation and through the channel, inlets to the 55 pressure chamber at opposite sides of said point or area of contact, and valve means associated with each of said inlets permitting entrance of fluid thereinto but preventing its exit therefrom, whereby when said rotating member rotates in 60 one direction, fluid will be drawn through one of said inlets and will be propelled through said channel and into said distributing chamber, while when said rotating member rotates in the opposite direction, fluid will be drawn through the 65 other of said inlets and will be propelled through said channels and into said distributing chamber.

2. A rotary pump comprising an inner member free to rotate in opposite directions and a casing surrounding said inner member and 70 spaced therefrom except at one area of contact as the inner member is rotated, to provide a pressure chamber between it and the inner member closed by such area of contact, and said pressure chamber being generally crescent shaped, a distributing chamber within said rotating

member, a channel connecting said chambers and a radially shiftable element carried by said inner member and automatically shiftable to position itself so as to propel the fluid in the pressure chamber in that direction in which the inner member is rotated regardless of the direction of rotation, said element also serving automatically to close the channel except in a direction from in front of said element as determined by the direction of rotation of said inner 10 member.

3. A rotary pump comprising an inner member free to rotate in opposite directions and a casing surrounding said inner member and spaced therefrom except at one point as the inner member 15 is rotated, to provide a pressure chamber between it and the inner member closed by such point of contact, and said pressure chamber being generally crescent shaped, a distributing chamber within said rotating member and a channel connecting said chambers and an element carried by said inner member and automatically shiftable to position itself as to propel the fluid in the pressure chamber in that direction in which the inner member is rotated regardless of the direction of rotation, said element being also laterally movable to automatically interrupt communication between the channel and the pressure chamber except in a direction from in front of said element as determined by the direction of rotation of 20 said inner member.

4. A rotary pump comprising an inner member free to rotate in opposite directions and a casing surrounding said inner member and spaced therefrom except at one area of contact 35 as the inner member is rotated, to provide a pressure chamber between it and the inner member closed by such area of contact, and said pressure chamber being generally crescent shaped, a distributing chamber within said rotating member, a channel connecting said chambers and an element carried by and moving with said inner member within the channel and adapted to protrude into the pressure chamber, and automatically operative to propel the fluid in the pressure 45 chamber in that direction in which the inner member is rotated regardless of the direction of rotation, said element being mounted for limited movement within said channel and thereby serving automatically to close the channel except in 50 a direction from in front of said element as determined by the direction of rotation of said inner member, whereby said elements serve automatically to propel the fluid in the direction of rotation and through the channel, inlets to the 55 pressure chamber at opposite sides of said point or area of contact, and valve means associated with each of said inlets permitting entrance of fluid thereinto but preventing its exit therefrom, whereby when said rotating member rotates in 60 one direction, fluid will be drawn through one of said inlets and will be propelled through said channel and into said distributing chamber, while when said rotating member rotates in the opposite direction, fluid will be drawn through the 65 other of said inlets and will be propelled through said channels and into said distributing chamber.

5. A rotary pump comprising an inner member free to rotate in opposite directions and a casing surrounding said inner member and spaced therefrom except at one area of contact as the inner member is rotated, to provide a pressure chamber between it and the inner member closed by such area of contact, and said pressure chamber being generally crescent shaped, a distributing 70 chamber within said rotating

- chamber within said rotating member, a channel connecting said chambers and a radially shiftable element carried by said inner member and automatically shiftable to position itself so as to 5 propel the fluid in the pressure chamber in that direction in which the inner member is rotated regardless of the direction of rotation, said element also serving automatically to close the channel except in a direction from in front of 10 said element as determined by the direction of rotation of said inner member, inlets to the pressure chamber at opposite sides of said point or area of contact, and valve means associated with each of said inlets permitting entrance of fluid 15 thereinto but preventing its exit therefrom, whereby when said rotating member rotates in one direction fluid will be drawn through one of said inlets and will be propelled through said channel and into said distributing chamber while 20 when said rotating member rotates in the opposite direction, fluid will be drawn through the other of said inlets and will be propelled through said channel and into said distributing chamber.
6. A rotary pump comprising an inner cylindrical rotating member having a distributing chamber therewithin, said member being surrounded by a cylindrical casing eccentrically po-

sitioned in relation thereto so as to touch it at one element of its periphery and said casing and said member having their end surfaces in fluid-tight contact, whereby a crescent-shaped compression chamber is formed between said casing and member, a passage in said member serving to connect said pressure chamber and said distributing chamber, movable piston means within said channel adapted to protrude into said pressure chamber when said member is rotating so as to drive before it fluid within said chamber and create a suction to the rear thereof, without obstructing said passage, valve means within said passage adapted to permit the passage of fluids into the distributing chamber when the pressure in the pressure chamber exceeds the force tending to close the valve, an inlet opening positioned on each side of said element of contact between the member and the casing, said inlet openings being spaced from each other, a conduit communicating with a supply of fluid lubricant associated with each inlet opening, a valve associated with each conduit permitting entry of lubricant into said pressure chamber but preventing its exit.

ALAIN MADLÉ. 25
